UNITED STATES PATENT OFFICE

2,328,231

SUPPORT FOR FILTERING APPARATUS

John George Royce, London, England, assignor of
one-half to The Paterson Engineering Com-
pany Limited, London, England

Application October 27, 1941, Serial No. 416,768
In Great Britain August 19, 1940

5 Claims. (Cl. 248—150)

This invention relates to filtering apparatus and has for its object to devise a conveniently portable installation such as can be readily and rapidly set up in any situation where it may be required for use and may be easily and rapidly dismantled to facilitate packing for transport either in panniers or packs carried on the backs of pack animals or in haversacks or other containers carried by human carriers.

The invention consists in a portable filter unit comprising a filter and brackets removably fixed thereto and adapted to take removable legs or supports forming a tripod or similar stand or support.

The invention also consists in filtering apparatus according to the preceding paragraph in which the removable brackets are carried by clamping bands secured to the body of the filter so that the bands and brackets may all be separately removed.

The invention also consists in filtering apparatus according to either of the two preceding paragraphs in which the unit is combined with a pump unit so that the combined filter and pump may be carried on a detachable tripod or stand.

Further features of the invention will be apparent from the description given hereafter.

The accompanying drawings illustrate one convenient form of apparatus in accordance with the invention.

Figure 1 is a perspective view of the complete apparatus.

Figure 2 is a plan.

Figures 3 and 4 are plan views on a larger scale of the two clamping bands shown in Figure 1.

Figure 5 is an enlarged view of a tripod leg, and

Figures 6 and 7 are enlarged views of a bracket to take a tripod leg.

In carrying my invention into effect in one convenient manner, I take any suitable filter unit *a* to the body of which I bolt two clamping bands *bc* spaced one above the other. Each of these clamping bands may have slots formed in it to take the supporting brackets *d* to which the tubular or other tripod legs *e* are attached. The slots *b*' in the band *b* are formed with parallel undercut side walls visible in Figure 3 while the walls of the slots *c*' in the band *c* are both undercut and inclined to present a dove-tail formation as clearly shown in Figures 1 and 4. In the particular construction illustrated each detachable supporting bracket has a rectangular end portion *d*' which slidably engages with the slot *b*' in the upper clamping band and which

is fitted with a spring catch *f* engaging the band for retaining the bracket in position until fully released. Each bracket is also fitted with a lower boss *d* formed to fit into the dovetailed tapered slot *c*' in the lower clamping band. The brackets *d* are socketed as at *d* to take the detachable legs *e* of the tripod which are held in position by gravity hooks *g* engaging in holes *e*' (Figure 5) drilled therein. The arrangement is such that the filter complete with supporting tripod can be freely moved about and when required the legs dismantled by throwing back the holding hooks *g*, and the supporting brackets may be withdrawn after releasing the spring catch *f*. At the lower end of each leg is hinged a foot support plate *h* of adequate area so constructed that it folds up relatively parallel with the leg when not in use as shown by the dotted lines in Figure 5, but is counterweighted so that when the leg is assembled with the filter unit the foot plate assumes a relatively horizontal position (as shown by the full lines in Figure 5) and prevents the leg sinking into the ground.

When it is desired that a combined filter and pump unit shall be detachably supported on a tripod or the like, I may provide a plate *i* adapted to be connected across the upper and lower clamping bands, and such plate is furnished with bosses *i*' by means of which a pump *k* of convenient form may be detachably secured to the plate while the latter is also detachably secured to the clamping rings.

If desired, the filter may be provided with interchangeable connections on inlet and outlet with caps for back flushing. Thus the connection from the pump to the filter inlet can be detached and coupled to the filter outlet, thus permitting back-wash through the filter from outlet to inlet to aid detachment of the filtering medium.

Any suitable frame or box may be provided for taking the components of a dismantled unit, also tool box, mixing tin and tin containing filter powder, water treatment chemicals and testing set.

It will be understood that the invention is not to be limited to the foregoing details of construction which are given by way of example only, as I may modify the means for detachably carrying the filter and pump upon a stand or tripod so that the parts may be readily dismantled for transport, depending upon the purposes for which the installation is to be employed.

I claim:

1. A support for portable filtering and like ap-

paratus, comprising two bands for removably clamping a part of the apparatus, brackets removably engaged with said bands, sockets carried by said brackets, supporting legs detachably engaged in said sockets, and gravity actuated catch members carried by said brackets for engaging and releasably retaining said legs in said sockets.

2. A support for portable filtering and like apparatus, comprising two bands for removably clamping a part of the apparatus, brackets removably engaged with said bands, supporting legs carried by said brackets, and plates pivoted to said legs and movable into a position perpendicular thereto to prevent sinking in soft ground.

3. A support for portable filtering and like apparatus, comprising two bands for removably clamping a part of the apparatus, brackets removably engaged with said bands, supporting legs carried by said brackets, and pivoted plates carried by said legs and counter-weighted and normally retained by gravity in a position perpendicular to said legs, said plates being movable into substantially parallel relation to said legs.

4. A support for portable filtering and like

apparatus comprising upper and lower bands for removable application to a part of the apparatus, the upper band being provided with slots having parallel undercut side walls and the lower band having dovetailed slots, brackets provided with rectangular upper portions slidably engaged in the slots of the upper band and having dovetail lower portions wedged in the slots of the lower band, and supporting legs carried by said brackets.

5. A support for portable filtering and like apparatus comprising upper and lower bands for removable application to a part of the apparatus, the upper band being provided with slots having parallel undercut side walls and the lower band having dovetailed slots, brackets provided with rectangular upper portions slidably engaged in the slots of the upper band and having dovetail lower portions wedged in the slots of the lower band, and supporting legs carried by said brackets, spring catches on the rectangular portions of said brackets adapted to snap over the upper band to retain said brackets in operative position, sockets of said brackets receiving said legs.

JOHN GEORGE ROYCE.
